UNITED STATES PATENT OFFICE.

MARSHALL C. LEFFERTS, OF NEW YORK, N. Y., ASSIGNOR TO THE ELECTRIC CUTLERY COMPANY, OF NEWARK, NEW JERSEY.

DESIGN FOR A RAZOR-HANDLE.

SPECIFICATION forming part of Design No. 21,015, dated August 25, 1891.

Application filed July 13, 1891. Serial No. 399,410. Term of patent 7 years.

To all whom it may concern:

Be it known that I, MARSHALL C. LEFFERTS, a citizen of the United States, residing in the city of New York, in the county and State of New York, have invented and produced a new and original Design for Handles of Razors, of which the following is a specification, reference being had to the accompanying drawing, illustrating my design.

10 My design consists of a conventionalized flower form *a* in rilievo, having pennant-like forms also in rilievo, and of rounded forms interspersed in the folds of the pennant forms at the front of the handle, and also of a some-
15 what conventionalized flower form *b* in rilievo, having pennant-like forms also in ri-

lievo, and of rounded forms interspersed in the folds of the pennant forms at the back of the handle.

What I claim is—

- 20 1. The design for handles for razors, consisting of the form *a*, substantially as shown.
2. The design for handles for razors, consisting of the form *b*, substantially as shown.
25 3. The design for handles for razors, consisting of the forms *a* and *b*, substantially as shown.

MARSHALL C. LEFFERTS.
